[57] ABSTRACT

An apparatus for use in selectively straightening any desired one of a number of metallic mandrels, which mandrels may vary in length, degree of taper, and diameter. Such mandrels are used in the manufacture of fishing rods to form tubular tapered sections from a resin impregnated fiber glass sheet.

The apparatus is adapted to removably grip a bent mandrel and power rotate the same on the longitudinal axis thereof, with the mandrel while so rotating having sequential sections of a selected longitudinal portion thereof subjected to a transverse bowing operation to straighten said portion. The apparatus is of such design that the magnitude of the transverse bowing of the portion being straightened varies as the straightening operation takes place, with the length of the bowed section decreasing as the diameter of said section decreases. Such variation in the degree of bowing of the sections has been found necessary to attain true straightening of a mandrel.

**APPARATUS FOR STRAIGHTENING METALLIC
FISHING ROD MANDRELS AND METHOD OF
USING SAME**

BACKGROUND OF THE INVENTION Art

1. Field of the Invention

An apparatus and method of using the same for straightening tapered elongate mandrels used in the production of sections of fishing rods from resin impregnated fiber glass sheets.

2. Description of the Prior ART

In the manufacture of high quality fishing rods by the use of tapered elongate metallic mandrels, it is of the utmost importance that such mandrels be maintained in a straight configuration. Frequently in the use of such mandrels they will be dropped or inadvertently subjected to forces that bend or deform the same, and until such mandrels are straightened they have no utility. Heretofore, no apparatus has been available that permitted a bent tapered fishing rod mandrel to be straightened in a short period of time, and with the person doing such straightening having little or no experience in this field. The present apparatus provides a device that may be readily employed by a person of but limited mechanical skill to straighten a tapered mandrel.

SUMMARY OF THE INVENTION

An apparatus for use in selectively straightening a desired longitudinal portion of a tapered fishing rod mandrel. The mandrel being straightened is removably gripped by a power driven chuck, and when so gripped and rotated has said portion subjected to a transverse bowing operation between a first roller and second and third longitudinally spaced rollers. The longitudinal spacing between the second and third rollers decreases as a carriage on which they are supported moves longitudinally towards the tip end of the rotating mandrel. Also, during the straightening operation the first roller moves towards the second and third rollers.

A major object of the present invention is to provide an apparatus and method of using the same for straightening any desired one of a number of fishing rod mandrels, which mandrels may vary in length, degree of taper and diameter, and with the apparatus capable of being successfully used for straightening such mandrels by a person having but a few minutes of training in the use thereof.

Another object of the invention is to supply a device for use in straightening fishing rod mandrels by rotating said mandrels on the longitudinal axis thereof, and sequentially subjecting longitudinal sections of the rotating mandrel to bowing operations that increase in severity as the tapered end of the mandrel is approached.

Yet another object of the invention is to provide an apparatus and method of using the same in straightening all or a portion of an elongate tapered metallic member of circular cross section used in the production of fishing rods, or in other precision manufacturing operations.

A further object of the invention is to supply fishing rod mandrels that are each identified with a particular insignia that is related to the length, degree of taper, and the diameter thereof, which insignia when matched with a second insignia on the apparatus, indicates the

length of the mandrel that should project from the rotating chuck to be subjected to a straightening operation.

A still further object of the invention is to supply a fishing rod mandrel straightening device in which a carriage moves on a longitudinal bed that forms a part thereof, and the carriage supporting first, second and third rollers that subject consecutive longitudinal sections of the mandrel to a bowing operation to straighten the same, but with the severity of the operation relative to a mandrel of a particular diameter being controlled by the length of the portion of the mandrel that projects from the chuck that removably rotates the mandrel.

BRIEF DESCRIPTION OF THE DRAWING

FIG. 1 is a perspective view of the fishing rod mandrel straightening device;

FIG. 2 is a top plan view of the device, with the carriage in a first position prior to the straightening operation being initiated;

FIG. 3 is a second plan view of the device, but with the carriage having moved longitudinally on the bed as a straightening operation on the mandrel takes place;

FIG. 4 is a fragmentary enlarged plan view of the bed of the device, with the roller supporting carriage exerting a transverse bowing operation on a section of the mandrel to straighten the latter;

FIG. 5 is a fragmentary side elevational view of the device;

FIG. 6 is a transverse cross sectional view of the device taken on the line 6—6 of FIG. 3;

FIG. 7 is a fragmentary transverse cross sectional view of the device taken on the line 7—7 of FIG. 4;

FIG. 8 is a fragmentary longitudinal cross sectional view of the power driven externally threaded rod in engagement with an internally threaded member that depends from the carriage;

FIG. 9 is the same view as shown in FIG. 8, but with the carriage being moved by the rotating threaded rod towards a first position that the carriage occupies prior to initiation of a mandrel straightening operation;

FIG. 10 is a top plan view of a set of spaced second insignia on the bed of the device, which when matched with first insignia on the mandrels, indicate the position the tip ends of the mandrels should occupy relative to the power driven chuck; and

FIG. 11 is a fragmentary side elevational view of a butt end of a mandrel that has a first insignia thereon.

**DESCRIPTION OF THE PREFERRED
EMBODIMENT**

The mandrel straightening device as may best be seen in FIGS. 1 to 3 includes an elongate horizontal bed B that is supported at a desired elevation above a floor (not shown) by legs C. A power driven chuck D is provided that has a bore 10 extending longitudinally therethrough. The mandrel E being straightened may be inserted through the bore 10 to have a portion of the mandrel occupy the position shown in FIG. 2.

First and second rails F and G are disposed on opposite sides of the bed B, and are supported by manually adjustable means H therefrom as shown in FIGS. 2 and 3. The first rail F tapers from a first end 12 of the bed inwardly towards a second end 14 of the bed as shown in FIG. 3. The second rail G tapers outwardly

from the first end 12 of the bed away from the second end 14 thereof.

A carriage J is supported on bed B for longitudinal movement thereon, with such longitudinal movement being provided by a power driven longitudinally extending threaded rod K as may best be seen in FIGS. 2 and 3. The carriage J as shown in FIG. 4 has first, second and third rectangular slides L, M and N respectively, movably supported thereon. A spring loaded pressure receiving member O is also mounted on the carriage as shown in FIG. 4. First, second and third rollers 16, 18 and 20 respectively, are rotatably supported on the first, second and third slides L, M and N as shown in FIG. 4. The second and third rollers 18 and 20 are longitudinally spaced and situated on opposite sides of the first roller 16. First spring means P are provided that at all times maintain a fourth roller 22 rotatably supported from the underside of the first slide L in contact with the inner edge of the first rail F. Second spring loaded means Q are pivotally mounted on the carriage J and connected to the first and second slides M and N to control the movement of the latter, spring loaded means Q includes fifth and sixth rollers 24 and 26 that are at all times in contact with the outer edge of the second rail G as shown in FIGS. 2 and 4.

The threaded rod K as can best be seen in FIG. 3 has first and second smooth surfaced end portions 28 and 30 respectively. First and second helical springs 32 and 34 encircle first and second end portions 28 and 30 as shown in FIG. 3, with the springs having ends 32a and 34a respectively that occupy fixed positions relative to the bed B. When the carriage J has moved longitudinally the length of the bed B due to engaging the rotating threaded rod K, the carriage contacts one of the springs 32 and 34 which is compressed. Upon the threaded rod K being rotated in an appropriate direction, the compressed spring 32 or 34 moves the carriage J in a direction to engage the threaded rod K, and the carriage then moves longitudinally on the bed B due to rotation of the threaded rod in a direction away from the compressed spring.

Each of the mandrels E as best seen in FIG. 11 has a first insignia 36 stamped or otherwise formed on the butt end 38 thereof. A second set of insignia 40 that are longitudinally and transversely spaced from one another as shown in FIG. 10 are visually displaced on the bed B as shown in FIG. 3. The mandrels E vary in length, degree of taper, and diameter at the butt ends thereof.

When a mandrel is extended through the chuck D as shown in FIG. 2, the correct length of the portion of the mandrel 42 that extends beyond the chuck D is determined by bringing the tip end 44 of the mandrel into transverse alignment with a comparable second insignia 40 that is identical to the first insignia stamped on the mandrel. Inasmuch as the mandrel E shown in FIG. 11 has the insignia 35 stamped on the butt end thereof, the tip 44 of the mandrel will be transversely aligned with the second insignia 35 as shown in detail in FIG. 10 and illustrated generally in FIG. 3. The first insignia takes into consideration the length of the mandrel the degree of taper of the mandrel, and the diameter thereof, and by experience it has been found that when the tip end of the mandrel 44 is aligned with the comparable second insignia 40, the projecting portion 42 of

the mandrel can be transversely bowed as the carriage J is driven towards the second end 14 of the bed, without the mandrel breaking.

This bowing and concurrent rotation of the mandrel portion 42 results in the straightening thereof. By experimentation, a person can determine the length of the portion 42 that extends beyond the chuck D for straightening purposes, but it is much easier and simpler to use the insignia code above described in arriving at the proper length for the mandrel portion 42.

The chuck D as may best be seen in FIG. 2 is supported from a shaft 46 that extends through a journal block 48 mounted on the first end 12 of the bed B. The shaft 46 is driven by a conventional gear reduction unit 50 shown in FIG. 1 that is supplied with power by an electric motor 52. The gear reduction unit 50 also by conventional means (not shown) serves to drive the threaded rod K. A manually operable control unit 54 of conventional design is provided that permits the threaded rod K to be selectively rotated in either a clockwise or counter clockwise direction, and also controls the rotation of the chuck D. The chuck D, shaft 46 and gear reduction unit 60 has a continuation 10a of the bore 10 extending therethrough, to permit a mandrel E to be inserted into the chuck or removed from the chuck by movement through the bore and bore extension.

The bed B is defined by two laterally spaced parallel structural member 56, preferably angle iron, that are secured at their ends to two cross pieces 58 as shown in FIG. 1 that have legs 60 extending downwardly therefrom to rest on the floor or supporting surface (not shown). The rails F and G as shown in FIGS. 2 and 6 have apertured lugs 62 depending from the end portions thereof that engage threaded horizontal rods 64 that extend outwardly in opposite directions from the members 56 as shown in FIG. 6. Lock nuts 66 are provided to engage the threaded rods 64 and hold the rails F and G at desired angulation relative to the bed member 56.

The carriage J as may be seen in FIGS. 4 and 6 includes a flat plate 68 that is slidably supported on the upper surface of the rigid member 56. The plate 68 has guides or rollers 70 extending downwardly from the undersurface thereof, that movably engage the edge surfaces 56a of the rigid members 56 to prevent lateral movement of the carriage J on these members as the carriage is moved longitudinally on the bed B due to rotation of the threaded rod K.

The first slide P is generally rectangular in shape and is supported on the upper surface of the carriage plate 68 between a pair of first guides 72 for transverse movement on the carriage. The first roller 16 is supported on the inner end of the first slide L on an upwardly extending stub shaft 74. A cross piece 78 extends between the first pair of guides 72 as shown in FIG. 4, and has a compressed helical spring 76 in abutting contact therewith. The spring 76 encircles a transversely positioned rod 78 that is secured to a protuberance 80 that extends upwardly from the outer end of the first guide L. The spring 76 at all times tends to move the first slide L outwardly, and in so doing maintains the roller 22 shown in FIG. 6 in contact with the inner edge 82 of the first rail F.

When the carriage J is disposed in a first position as illustrated in FIG. 2, the compressed helical spring 76 moves the first slide L outwardly due to the fourth roller 22 entering a recess 82a in the first rail F, and the first slide L and first roller 16 being then so positioned that the first roller 16 exerts no force on the mandrel E. The mandrel E can now be slid longitudinally through the bore 10 and extension 10a to disengage it from the second and third rollers 18 and 20. Likewise when the carriage J is in the first position as shown in FIG. 2, a mandrel E may be inserted through the bore 10 and extension 10a to extend between the first roller 16 and second and third roller 18 and 20.

The carriage J has two guide blocks 84 mounted in fixed positions thereon as shown in FIG. 4 which guide blocks have aligned openings 84a extending longitudinally therethrough, which openings slidably and rotatably engage the mandrel portion 42 and assist in directing the mandrel portion between the first roller 16 and second and third rollers 18 and 20 prior to initiation of the bending operation. Pairs of second and third guides 86 and 88 respectively, are secured to the upper surface of the carriage plate 68 and serve to support the second and third guides M and N. The second and third guides M and N are of generally rectangular shape as shown in FIG. 4. The second and third slides M and N have links 90 pivotally connected to the outer ends thereof, and these links 90 also being pivotally connected by pins 92 to inwardly extending arms 94 that form parts of two Z-shaped members 96 that are pivotally supported on pins 98 that engage the bed B. The Z-shaped members 96 include outwardly extending arms 100 that have the rollers 24 and 26 rotatably supported in depending positions therefrom. The Z-shaped members 96 have pins 102 extending upwardly therefrom that are engaged by a longitudinal tensioned helical spring 104. Tensioned spring 104 at all times tends to pivot the Z-shaped members in a direction that the outwardly extending arms 100 approach one another.

Due to the tensioned spring 104 it will be seen in FIG. 2 that the outwardly extending arms are substantially parallel to one another when the carriage J is in the first position as shown in FIG. 2, and the second and third rollers 18 and 20 are at maximum longitudinal spacing from one another. The carriage plate 18 as shown in FIG. 6 has an internally threaded member 106 depending therefrom that engages the threaded rod K, with the carriage being moved longitudinally on the bed B when the threaded rod is rotated. The end of rod K most remote from chuck D is rotatably supported in a journal block 105.

As the carriage J is moved longitudinally on bed B towards the second end 14 thereof, the rollers 24 and 26 are in engagement with the second rail G, and the Z-shaped members 96 are pivoted in opposite directions to force the second and third slides M and N respectively, together with the second and third rollers 18 and 20, towards one another. As this longitudinal movement takes place, the rail F forces the first slide L and first roller 16 towards the pressure receiving member O, to exert a bow in the mandrel portion 42 being straightened. As the diameter of the mandrel portion 42 decreases, the severity of the bow formed therein increases, due to the second and third rollers 18 and 20

moving towards one another and the first roller 16 moving towards the pressure receiving member O.

Such bowing of the mandrel portion 42, together with the rotation thereof results in said portion being straightened. The pressure receiving member O is of arcuate shape, and is mounted on one end of a transversely positioned rod 108 that is slidably mounted in a transverse bore (not shown) formed in a third block 110 that is secured to the upper surface of the carriage plate 68. A compressed helical spring 112 encircles the rod 108, and has the ends thereof in abutting contact with the pressure receiving member O and the third block 110. The first, second and third rollers 16, 18 and 20 are each formed with circumferentially extending grooves 114 therein as best seen in FIG. 7, which grooves engage the mandrel portion 42 to maintain it in centered relationship with the rollers. The first and second rails F and G are adjustable as to angulation relative to bed B, with the angulation being so selected that the mandrel portion 42 being straightened will be sequentially bowed as it rotates, but without this bowing being so severe as to cause the breakage thereof.

The use and operation of the invention has been previously described and need not be repeated.

I claim:

1. A device for selectively straightening elongate metallic mandrels of different lengths, tapers and diameters the type used in forming rods, each of said mandrels having a tip and a butt end which device includes:
  - a. an elongate bed having first and second ends;
  - b. a power driven chuck transversely centered at said first end of said bed, said chuck having a passage extending longitudinally therethrough and said chuck capable of removably engaging any desired longitudinal section of one of said mandrels;
  - c. first and second rails on opposite longitudinal sides of said bed and spaced therefrom, and first rail tapering towards said second end, and said second end tapering towards said first end;
  - d. a carriage longitudinally movable on said bed;
  - e. first power means for moving said carriage longitudinally on said bed;
  - f. first, second and third slides movably mounted on said carriage, said first slide transversely movable relative to said carriage, and said second and third slides longitudinally movable on said carriage and spaced from one another;
  - g. an arcuate spring loaded pressure receiving member disposed between said second and third rollers and transversely aligned with said first rollers;
  - h. first, second and third rollers rotatably supported on said first, second and third slides;
  - i. first spring loaded means secured to said first slide that are at all times in pressure contact with a longitudinal edge of said first rail;
  - j. second spring loaded means secured to said carriage that are connected to said second and third slides and are at all times in contact with said second rail and move second and third slides and second and third rollers away from one another as said carriage moves towards said second end;
  - k. first means for stopping said carriage at first and second positions adjacent said first and second

ends after said carriage has at least partially traversed the longitudinal length of said bed, with said mandrel when rotated by said chuck, and when in contact with said first, second and third rollers and pressure receiving member as said carriage moves from said first towards said second position having consecutive longitudinal sections thereof sequentially bowed to varying degrees as said first roller is moved transversely towards said pressure receiving member and said second and third rollers move away from one another, with said bowing and rotation of said mandrel cooperating to straighten the latter; and

e. second means operatively associated with said bed for indicating the position a tip of one of said mandrels of a particular length and taper should occupy relative to said chuck.

2. A device as defined in claim 1 in which each of said mandrels carries a first insignia that indicates the length, degree of taper and diameter of the butt end thereof and said second means are a plurality of longitudinally spaced second insignia on said bed that are the same as said first insignia, with the positioning of said tip of one of said mandrels relative to said chuck being correct when the tip of said mandrel is transversely aligned with a one of said second insignia that is the same as said first insignia carried on said mandrel.

3. A device as defined in claim 1 in which said first power means includes:

- m. an internally threaded member depending from said carriage;
- n. an elongate threaded rod rotatably supported from said bed and engaging said threaded member, said rod longitudinally positioned relative to said bed;
- o. a reversible electric motor;
- p. a gear reduction unit that is power transmitting connected to said chuck and to said threaded rod and is driven by said motor; and
- q. manually operated control means for selectively actuating said chuck and threaded rod to move said carriage at a desired direction on said bed.

4. A device as defined in claim 3 in which said threaded rod has first and second smooth surfaced end portions, and said first means are first and second helical springs that encircle said first and second end portions and are contacted by said carriage after it has traversed the length of said bed, with the ends of said springs not contacted by said carriage occupying fixed positions relative to said bed, and said springs when said threaded rod is rotated in an appropriate direction forcing said threaded member to reengage said threads on said rod for said rod to move said carriage longitudinally on said bed.

5. A device as defined in claim 1 in which said first

slide is rectangular in shape and transversely disposed on said carriage and said first spring loaded means includes:

- m. two transverse longitudinally spaced first quides on said carriage that movably support said first slide therebetween;
- n. a crosspiece extending between said guides;
- o. a protuberance on an outer end of said first slide;
- p. compressed spring means extending between said crosspiece and protuberance;
- q. a stub shaft depending from an outer end of said slide; and
- r. a fourth roller rotatably supported on said first stub shaft that is at all times maintained in contact with said first rail by said compressed spring means.

6. A device as defined in claim 5 in which said first rail has a transverse opening therein adjacent said chuck into which opening said fourth roller may enter to move said first roller transversely to the extent that said mandrel may be disengaged from said first, second and third rollers after said mandrel is straightened.

7. A device as defined in claim 1 in which second and third guides are rectangular in shape and said second means includes:

- m. second and third pairs of guides that movably support said second and third slides on said carriage;
- n. first and second Z-shaped cranks pivotally supported on said carriage, each of said cranks including a transverse outwardly extending arm and a transverse inwardly extending arm;
- o. first and second links pivotally connected to said second and third slides and to the inwardly extending arms of said first and second cranks;
- p. tensioned spring means that tend at all times to move said second arms of said first and second cranks towards one another; and
- q. fifth and sixth rollers rotatably supported from said outwardly extending arms of said first and second cranks that are at all times in pressure contact with said second rail due to said tensioned spring means.

8. A device as defined in claim 7 which in addition includes:

- r. first and second guide blocks supported from said carriage that have said second and third rollers situated therebetween said guide blocks having openings therein that are slidably and rotatably engaged by said mandrel being straightened.

9. A device as defined in claim 1 which in addition includes:

- m. third means for adjustably supporting said first and second rails at a desired angulation relative to said bed.
